UNITED STATES PATENT OFFICE.

JOHN A. ERICKSON, OF MALDEN, MASSACHUSETTS.

SIGHT-FEED FOR LUBRICATORS.

No. 823,209.

Specification of Letters Patent.

Patented June 12, 1906.

Application filed March 5, 1906. Serial No. 304,179.

To all whom it may concern:

Be it known that I, JOHN A. ERICKSON, a citizen of the United States, residing at Malden, county of Middlesex, and State of Massachusetts, have invented an Improvement in Sight-Feeds for Lubricators, of which the following description, in connection with the accompanying drawings, is a specification, like numerals on the drawings representing like parts.

This invention relates to lubricators, and especially to the type known as "force-feed" lubricators; and its principal object is to so arrange the parts that the sight-tube will be situated in a pipe which is constantly filled with water so cool as to prevent the oil in passing through the sight-tube from emulsifying.

In accordance with my invention I provide the oil-supply pipe which connects the pump or forcing mechanism to the steam-main with an enlarged chamber and place the sight-tube in said oil-supply pipe between the chamber and the forcing mechanism and a sufficient distance from the chamber so that the oil will not be heated, and I also connect said chamber, preferably at its side, with the steam-main by means of another pipe. The last-named pipe and the portion of the oil-supply pipe between the chamber and the steam-main constitutes a by-pass in which condensation water accumulates. The water in the pipes between the chamber and steam-main is at a more or less elevated temperature; but the water which accumulates in the oil-supply pipe between said chamber and the forcing mechanism does not circulate at all and remains cool, and as the sight-tube is situated between said chamber and the forcing mechanism the oil does not become emulsified while passing through the sight-tube.

With my improvement, therefore, the sight-tube is always clear and transparent. In the drawings, Figure 1 is a view showing the general arrangement of parts of my improvement; and Fig. 2 is a section on the line *xx*, Fig. 1

3 designates the steam-main which leads from the boiler or other source of steam-supply to the engine or other mechanism to be operated by the steam. 9 designates an oil-supply pipe which connects the steam-main 3 with the forcing mechanism or pump (not shown) by which the oil is forced into the steam-main. Situated in the oil-supply pipe 9 is a chamber 4, in the bottom and top of

which the said pipe 9 enters. For convenience I have designated the portion of the pipe 9 between the chamber 4 and the steam-main by the reference-numeral 7, said pipe-section 7 communicating with the steam-main at 8. 5 designates another pipe which communicates with the steam-main at 6 and also communicates with one side of the chamber 4. The pipe 5 and the pipe-section 7 form a sort of by-pass, and as steam enters said pipes it will gradually condense until the water of condensation fills the pipe 9, chamber 4, and the pipe-sections 5 and 7 up to about the level of the line *a b*. 10 designates a sight-tube which is situated in the oil-supply pipe 9 between the chamber 4 and the forcing mechanism.

While the engine is running and oil is being delivered to the steam-main 3 there will be a slow circulation of water through the pipes 5 and 7 and the chamber 4, as indicated by the arrows in Fig. 1. The water thus circulating will of course be very hot; but since the sight-tube 10 is situated entirely below the chamber 4 this circulation of hot water does not affect the temperature of the dead water in the oil-supply pipe 9, which remains perfectly cool.

In sight-feeds for lubricators that I am familiar with the sight-tube is so arranged that the hot water of condensation circulates therethrough. When this occurs, the oil becomes more or less emulsified and the sight-tube becomes so clouded that it is impossible to observe properly the amount of oil delivered. This difficulty is entirely overcome by my invention, because the water in the sight-tube is always cool.

The sight-tube may be mounted in any suitable way. I have, however, herein shown it as having its ends received in two holders 14, which are connected by tubular arms 15. The ends of the sight-tube abut against heads 17 to which the sections of the oil-supply pipe 9 are attached, and these heads are clamped together by means of suitable bolts or rods 20, which extend through the tubular arms 15.

21 21 designate packing-rings which are received between the holders 14 and heads 17 and which form a tight joint around the sight-tube 10. The lower head 17 is provided with the usual nozzle 23.

The baffle-plate 11 prevents the oil from passing into the pipe 5 and assists in maintaining proper circulation of steam.

Having fully described my invention, what I claim as new, and desire to secure by Letters Patent, is—

1. In a device of the class described, a steam-main, an oil-supply pipe connected thereto, said pipe having an enlarged chamber, another pipe also connected to the steam-main and communicating with said chamber, and a sight-tube located in the oil-supply pipe between the chamber and the source of oil-supply.
2. In a device of the class described, a chamber, two pipes both connected with the steam-main, one entering the top of the chamber and the other the side thereof, an oil-supply pipe communicating with the bottom of the chamber, and a sight-tube within the oil-supply pipe and situated some distance below the chamber, said chamber having a transversely-arranged baffle opposite the pipe which enters the side thereof.
3. In a sight for a lubricator, two heads, a

sight-tube situated between said heads, one of said heads having a nozzle entering one end of the sight-tube, a holder surrounding the ends of the sight-tube and interposed between the heads, and bolts connecting the heads.

4. In a sight for a lubricator, two heads, a sight-tube situated between said heads, one of said heads having a nozzle entering one end of the sight-tube, a holder surrounding the ends of the sight-tube and interposed between the heads, and bolts connecting the heads, said bolts passing through tubular posts forming part of the holder.

In testimony whereof I have signed my name to this specification in the presence of two subscribing witnesses.

JOHN A. ERICKSON
